US00D906416S

(12) **United States Design Patent** (10) Patent No.: **US D906,416 S**
(45) Date of Patent: **** Dec. 29, 2020**

(54) **INK CARTRIDGE FOR COMPUTER PRINTERS**

(71) Applicant: **CANON KABUSHIKI KAISHA**,
Tokyo (JP)

(72) Inventors: **Takashi Fukushima**, Yokohama (JP);
Yasuo Kotaki, Yokohama (JP); **Tetsuya Ohashi**, Matsudo (JP); **Ryoji Inoue**, Kawasaki (JP); **Hironori Murakami**, Meguro-ku (JP); **Takeho Miyashita**, Yokohama (JP); **Kyosuke Nagaoka**, Kodaira (JP)

(73) Assignee: **Canon Kabushiki Kaisha**, Tokyo (JP)

(**) Term: **15 Years**

(21) Appl. No.: **29/747,017**

(22) Filed: **Aug. 19, 2020**

Related U.S. Application Data

(62) Division of application No. 35/507,171, filed on Sep. 28, 2018 (U.S. filing date under 35 U.S.C. 384), and having an international filing date of Sep. 28, 2018.

(57) **CLAIM**

The ornamental design for an ink cartridge for computer printers, as shown and described.

DESCRIPTION

FIG. 1: Front view of the ink cartridge for computer printers;
FIG. 2: Back view thereof;
FIG. 3: Top view thereof;
FIG. 4: Bottom view thereof;
FIG. 5: Left view thereof;
FIG. 6: Right view thereof;
FIG. 7: Perspective view thereof;
FIG. 8: Perspective view thereof;
FIG. 9: Perspective view thereof;
FIG. 10: Enlarged view of FIG. 2; and,
FIG. 11: Enlarged view of FIG. 5.

The broken lines show portions of the ink cartridge for computer printers that form no part of the claimed design.

1 Claim, 11 Drawing Sheets
